Attest,

UNITED STATES PATENT OFFICE.

FREDERIC S. SEAGRAVE, OF ROCHESTER, MICHIGAN.

TRUSSLED LADDER.

SPECIFICATION forming part of Letters Patent No. 267,803, dated November 21, 1882.

Application filed April 13, 1882. (No model.)

To all whom it may concern:

Be it known that I, FREDERIC S. SEAGRAVE, of Rochester, in the county of Oakland and State of Michigan, have invented new and useful Improvements in Trussed Ladders; and I do hereby declare that the following is a full, clear, and exact description thereof, reference being had to the accompanying drawing, which forms a part of this specification.

10 The nature of this invention relates to certain new and useful improvements in the construction of ladders, by means of which deflection, by the imposed weight upon the ladder is avoided as well as all tendency to lateral swaying.

15 The invention consists in so trussing a ladder as to prevent deflection by the superimposed weight and side or lateral swaying of the latter. Ladders of extraordinary length have been trussed heretofore by a distinct and separate truss upon each leg of the ladder. Such trussing would to a very large degree prevent deflection; but under no circumstances would it have any effect upon the lateral or side-swaying motion of the ladder when in use.

20 The object of my invention, therefore, is to overcome both these difficulties.

25 In the accompanying drawing, my invention is shown in a perspective elevation, taken from

the rear. A A' represent the two legs of the 30 ladder, provided with the usual rounds, B. Midway between the ends of the legs is rigidly attached or secured the bridge C, made in an arched form, substantially as shown. A truss-rod, D, is secured at each end near the ends of 35 the leg A, and leads to a central point on the rear of said bridge. A similar truss, E, is similarly secured to the leg A', and at the central point of meeting of these two trusses upon the bridge they are secured thereto in this manner, the two truss-rods forming a truss which prevents the ordinary deflection of the ladder, and as the truss-rods run from this given center outwardly and radially to the ends of the legs of the ladder all tendency to side sway or 40 rocking motion is avoided.

45 What I claim as my invention is—

The combination, with the legs A A' of a ladder, of the central cross-bar, C, and the truss-rods D E, each secured at its ends to opposite ends of the legs, and both secured at their middle to the center of the cross-bar C, substantially as described.

FREDERIC S. SEAGRAVE.
